UNITED STATES PATENT OFFICE.

RICHARD V. MATTISON, JR., OF UPPER DUBLIN TOWNSHIP, MONTGOMERY COUNTY, PENNSYLVANIA.

MECHANISM FOR APPLYING DRY COLOR TO ASBESTOS-CEMENT SHEETS.

1,326,362.

Specification of Letters Patent.

Patented Dec. 30, 1919.

Application filed February 12, 1919. Serial No. 276,680.

To all whom it may concern:
Be it known that I, RICHARD V. MATTISON, Jr., a citizen of the United States, residing in Upper Dublin township, in the county of 5 Montgomery and State of Pennsylvania, have invented certain new and useful Improvements in Mechanism for Applying Dry Color to Asbestos-Cement Sheets, whereof the following is a specification, reference 10 being had to the accompanying drawings.

To color asbestos cement sheets the coloring matter is applied very evenly and by means of a brush to the asbestos cement sheets while they are still somewhat damp 15 from the process of manufacture. The asbestos cement sheets may or may not be subdivided into sections in the form of tiles or shingles. According to my invention I provide means for carrying the asbestos cement sheets beneath a rotary brush by which 20 the color is applied. The dry coloring matter is fed to this brush by means which admit of accurate control of the rate of supply. A second rotary brush turning in the direction opposed to that of the first mentioned 25 one completes the even distribution of the coloring matter upon the surface of the asbestos cement sheets.

In the accompanying drawings, I have 30 illustrated an embodiment of my invention in which Figure I, is a longitudinal sectional view of the mechanism.

Fig. II is an elevation showing certain parts in cross section along the line II, II, 35 of Fig. I.

The asbestos cement sheets are fed as by an apron 1, and bridge 2, to an endless carrying apron 3, running upon and driven by the roller 4. Support is given to the apron 40 3, sufficient to enable it to hold its load of asbestos cement sheets by means of the plate 5, immediately below the upper half of the traveling apron and the apron is kept taut by an idler roll 6, pivoted upon the swinging 45 arms 7, so that its weight depends upon the lower or return half of the traveling apron.

The rotary coloring brush 8, is mounted 50 between the housings 9, which are erected one on either side of the traveling apron. A similar rotary coloring brush 10, is likewise mounted between the housings 9, in succession to the brush 8.

The brush 10, is driven by a sprocket drive 11, so as to rotate as indicated by the arrow 55 in opposition to the travel of the apron.

The brush 8, is geared to brush 10, by the companion gears 18, and 19, by which said brush 8, is caused to rotate in correspondence with the travel of the apron and at a more rapid speed than brush 10. The bristles of 60 the brush 10, are preferably longer than those of brush 8.

Dry coloring matter is continuously fed in regular quantities to the top of the brush 8, from the color reservoir 12. The lower 65 end of this color reservoir has a slotted aperture within which rotates, fitting with precision, the channeled cylinder 13. On the feed side the surface of this channeled roller is protected by the plate or overhang 14, 70 formed upon the lower side of the color reservoir. The parts which have just been described are supported by the housings 9, and immediately superimposed upon the rotary color brush 8, so that as the channeled 75 roller 13, rotates, the dry coloring matter received within its channels is carried down to and discharged upon the upper surface of said brush and by it carried around and brushed upon the upper surface 80 of the asbestos cement material which it is desired to color, as it travels at a less rate of speed beneath the brush.

The difference in linear velocity of the 85 acting surfaces of the rotating brushes facilitates passage of the asbestos cement sheet material beneath them, since the tendency of the brush 8, to impel or feed the material to the right more than offsets the tendency of the brush 10, to feed it in the reverse direction.

It is important that the rate at which the dry coloring matter is fed to the asbestos cement sheets should be accurately regulated, otherwise satisfactory results cannot 95 be obtained. To this end the slot in the bottom of the color reservoir 12, within which runs the channeled cylinder 13, is provided at either end with segmental shutters 15, which can be moved toward or away 100 from each other, in such a way as to uncover more or less of the grooved surface of the underlying cylinder so as to regulate the amount of dry coloring matter discharged through the bottom of the color reservoir. 105 These shutters are hinged as at 16, and are moved by a handle 17, set upon the projecting end of their pivots. The rate of supply of the coloring matter is further dependent upon the speed with which the 110

grooved cylinder 13, rotates and this is regulated as follows: Said grooved cylinder is driven by a worm gear 20, driven by a worm 21, on the shaft 22, upon which is splined 5 the shaft 23, movable longitudinally thereon, by the hand lever 24, the yoked extremity of which engages a suitable collar attached to said disk. The perimeter of the disk 23, bears against the surface of the disk 10 24, set under tension of the spring 25, upon the shaft which carries the rotary brush 10, from which said grooved cylinder derives its motion, the rate of speed depending upon the adjustment between the disks 23, and 24, 15 which can be regulated at the will of the operator. By means of such regulation in combination with the additional regulation obtained by varying the position of the shutters 15, I secure a very accurate determination 20 of the exact quantity of coloring matter fed to the brush and therefore applied to the upper surface of the asbestos cement sheets, as they travel beneath the brushes.

Having thus described my invention, I 25 claim:

1. In a device of the class described, the combination of a color reservoir; an aperture in the base thereof; a grooved cylinder rotating in said aperture; a rotary color brush rotating below said grooved cylinder; means for carrying surfaces to be colored in contact with said rotary brush; and means for regulating the speed with which the grooved cylinder rotates.
- 35 2. In a device of the class described, the combination of two color brushes rotating in opposite directions; means for continuously moving surfaces to be colored into contact with such brushes successively; a color reservoir having an opening at the 40 bottom thereof and a grooved cylinder ro-

tating within said aperture, and having the lower side of its perimeter so closely related to the first of the rotary color brushes as to deposit upon said brush the coloring matter which said grooves receive as they pass through the reservoir.

3. In mechanism for applying dry color to sheet material, the combination of rotary color brushes rotating in opposite directions 50 with different surface speeds, means for carrying the sheet material past said brushes in succession, so that it may move in the same direction as the more rapidly moving brush surface, and means for supplying dry 55 coloring matter to be brushed upon the sheet material by said brushes in succession.

4. An apparatus in accordance with claim 3, wherein the more rapidly moving brush is the first to act on the sheet material and the 60 coloring matter is supplied to it and by it supplied upon the sheet material.

5. In mechanism for applying color to moving surfaces, the combination of means for effecting continuous travel of said surfaces to be colored; two successive color brushes rotating in contact with said moving surfaces, the first of said brushes having its contacting surface moving in the same direction as the surface to be colored, but 70 more rapidly than it, the second of said brushes rotating less rapidly than the first and in the opposite direction; and means for supplying coloring matter to the first of said brushes.

In testimony whereof I have hereunto signed my name at Philadelphia, Pennsylvania, this tenth day of February, 1919.

RICHARD V. MATTISON, JR.
